(57) **CLAIM**

The ornamental design for a container for an industrial process, as shown and described.

DESCRIPTION

FIG. 1 is a perspective view taken from a front, left side of a container for an industrial process according to a second embodiment of my design;

FIG. 2 is a left side elevation view thereof;

FIG. 3 is a right side elevation view thereof;

FIG. 4 is an end view of a rear elevation view thereof;

FIG. 5 is an end view of a front elevation view thereof; and,
FIG. 6 is a top plan view thereof.

Throughout the Figures, where shown, the broken lines are included for the purpose of illustrating portions of the container for an industrial process which form no part of the claimed design.
